UNITED STATES PATENT OFFICE

LEIGH W. HOSTETTLER, OF TARENTUM, PENNSYLVANIA, ASSIGNOR TO ALLEGHENY STEEL COMPANY, OF BRACKENRIDGE, PENNSYLVANIA, A CORPORATION OF PENNSYLVANIA

CLOSING MEANS FOR JOURNAL-BOX LIDS

Continuation of application Serial No. 603,003, filed November 24, 1922. This application filed March 8, 1923. Serial No. 623,668.

This invention relates to journal boxes and more particularly to improvements in journal box lids and closing means for such lids.

An object of this invention is to provide a simple journal box lid and closing means for such lid which will insure seating of the lid over the entire journal box face, that is, on the top face as well as the bottom and side faces.

Another object of this invention is to provide a journal box lid which is directly hinged to the lid hinge pin and closing means for the lid which is so associated with the lid as to hold it either fully closed or fully opened and when closed is so arranged that the pressure it exerts is applied to the center of the lid in such manner that the lid will seat itself on the top as well as the bottom and sides of the lid opening.

A still further object of this invention is to provide a journal box lid and closing means therefor which may be applied to journal boxes now commonly used without any particular fitting whereby such variations as occur will be accommodated and a full seating of the lid on the entire journal box face assured.

A still further and more specific object of this invention is to provide a journal box lid of the hoodless type and closing means therefor by means of which the lid opening of a journal box may be completely closed even though relatively great clearances exist between the lid scrolls or between the hinge pin and the box lug pin-hole or both.

These objects, as well as others, I attain by means of the device described in the specification, illustrated in the drawings accompanying the same and particularly pointed out in the appended claims.

In the drawings, Figure 1 is a front view in elevation of a hoodless type of lid and a spring actuated device therefor embodying this invention;

Figure 2 is a view in side elevation of the device illustrated in Figure 1;

Figures 3 and 4 are views taken on the longitudinal center line of the lid and illustrate the method of springing the tensioning

member of the lid-closing device into operative position; and

Figure 5 is a view in side elevation of the lid and a portion of a journal box taken on the longitudinal center line of the lid and shows the lid in open position.

In the drawings I have shown the invention in connection with a pressed metal lid and a standard A. R. A. journal box. This is done, however, without any idea of limiting the invention to a pressed metal lid or use with such a journal box.

The lid, as illustrated, is provided with a flat surface 7 adapted to bear evenly on the flat faces 8 defining the lid opening of the journal box. The journal box is provided with a box lug 10 having the usual flat angularly disposed bearing or cam faces 11 and 12.

The lid proper is provided with spaced scrolls 14 which are preferably reinforced by means of reinforcing ribs 15 as shown in Patent No. 1,425,093, issued to me on August 8, 1922, and the scrolls are also preferably provided with hinge pin retaining ears 15^a, as shown in Patent No. 1,425,092, issued to me on the same day.

The lid scrolls are elongated perpendicularly to the general plane of the lid proper and embrace the hinge pin which projects through and beyond the opposite ends of the box lug 10. The clearances between the scrolls and hinge pin are relatively great as clearly shown by full lines in Fig. 2 of the drawings and by dotted lines in Figs. 3, 4 and 5 thereof.

The lid is provided with a depending guard flange 17 and with a projecting lip 18 by means of which it may be lifted or opened. It is also preferably reinforced or stiffened by means of depressions 19 which are pressed into the lid during its formation.

The lid closing means or device includes a spring 20, a spring retainer or tensioning member or stirrup 21 and an anti-friction roller 22. While the spring forming part of the lid-closing means may be of various forms, the one illustrated is provided with two coils 23 located on opposite sides of the median line of the lid and having a common major axis which is parallel to the hinge pin

axis. The spring is formed from a single piece of wire of suitable cross section and its coils are joined at their inner ends 24 by means of a connecting portion 25 which is substantially straight from end to end. The outer ends 20 of the coils are longer than the inner ends 24 and are bent one toward the other.

The outer ends of the spring are covered by means of a retaining plate 29 secured to the lid by rivets 30. The lid beneath the retaining plate is provided with a depression within which the ends of the spring lie. The depressions and retaining plate serve to provide a pivotal connection between the spring and the lid. Anti-friction roller 22 is pierced to receive the cross connecting member 25 of the spring and the roller is threaded onto the spring wire before the wire is bent to form.

The retainer 21 when in operative position not only serves as a retainer, but also as a spring tensioning member. It is formed so as to fit the outer portion of the spring coils 23 and is supported from the hinge pin by strap members 34 which are pierced to receive the hinge pin and which lie between the inner ends of scrolls 14 and the adjacent ends of the box lug. The retainer is mounted on the hinge pin independently of the lid proper and when forced into operative position, causes the spring 20 of the lid closing device, (when the lid is in closed position) to exert its pressure at the center of the lid in such manner that the lid will seat itself evenly on the top, bottom and sides of the box face even though relatively great clearances exist between the lid scrolls and the hinge pin or between the hinge pin and the box lug pin-hole or both. As before stated, relatively large clearances between the lid scrolls and the hinge pin are provided in order to insure the even bearing of the lid on the top, bottom and sides of the box face even in those cases where the hinge pin is out of line.

When the lid is in closed position, anti-friction roller 22 bears on bearing face 11 of the box lug and when in open position, on bearing face 12. When the lid is moved from one position to the other, the roller 22 rolls on the bearing faces. Since the bearing face 11 which is substantially flat, stands at a slight angle to the plane of the box face, the lid in closing is allowed free movement. The roller 22 rolls down the inclined face and thus prevents drag between the lid closing device and the box lug, assuring maximum spring action on the lid when the lid is in closed position.

By reason of the elongated scrolls (which provide relatively great clearances perpendicular to the general plane of the lid) and the action of the lid closing device, I provide a self-fitting lid having a center pressure spring action, that is a lid in which the spring action is exerted at the center of the lid as distinguished from the lid closing devices

which tend to lift or pull the upper part of the lid away from the top of the box face.

In order to apply the lid and its closing means in the field, a tool 36 resembling a short pinch bar, is provided by means of which the retainer or tensioning member 21 may be readily forced into position in the manner graphically illustrated in Figs. 3 and 4.

After the lid with the spring 20 attached thereto is placed in position on the journal box, the straps of the tensioning member 21 are inserted between the lid scrolls and the box lug and the hinge pin is inserted through the lid scrolls and the straps. By means of the tool 36 the tensioning member 21 may then be forced into position over the spring coils.

This application is a continuation of an application filed by me on Nov. 24, 1922.

It will be understood that various forms and types of springs may be used without departing from the spirit of this invention and the spring tensioning member may, of course, be varied to suit the type and form of spring used.

Having thus described my invention, what I claim is:—

1. The combination with a journal box having a standard A. R. A. box lug, of a hinge pin extending through said lug and beyond the ends thereof, a lid having elongated scrolls surrounding said pin on opposite sides of the lug and spaced therefrom and a spring device for applying a substantially equally distributed yielding pressure against the outer face of the lid adjacent its center; said spring device having a central portion thereof bearing on the box lug, another portion thereof operatively positioned in the outer face of the lid adjacent its center and two other portions surrounding the hinge pin and located between the ends of the box lug and the scrolls.

2. The combination with a journal box having a hinge pin lug, of a lid hinged to the lug, a lid closing spring at one end operatively engaging the outer face of the lid and at the other end operatively engaging the lug, and tensioning means for said spring pivotally connected to the lug and engaging said spring intermediate its ends.

3. The combination with a journal box having a hinge pin lug, of a hinge pin extending beyond said lug, a box lid mounted on said pin, lid closing means at one end operatively positioned in the outer face of the lid intermediate its top and bottom edges and tensioning means for said lid closing means mounted on said pin and engaging said lid closing means intermediate its ends.

4. The combination with a journal box, of a hinge pin extending through the lug thereof, a lid having hinge pin engaging portions engaging the hinge pin with relatively great clearances, a lid closing agent at one end oper-

- atively engaging the lid adjacent its center and at the other end terminating adjacent the box lug, an anti-friction member interposed between the box lug and the adjacent end of said agent and a tensioning member for said agent mounted on the hinge pin and arranged to engage said agent intermediate its ends.
5. In combination with a journal box provided with a lug having a plurality of bearing faces, of a lid for closing said box and provided with scrolls located on opposite sides of said lug, a pin for pivotally connecting said scrolls to said lug, spring means at one end attached to the outer face of said lid and at the other end terminating adjacent said lug, an anti-friction roller carried by said spring means and interposed between the box lug and the adjacent end of said spring and a tensioning member for said spring means carried by said pin and arranged to bear on said spring means intermediate its ends and on the opposite side thereof from said lid.
10. In combination with a journal box having a box lug provided with a plurality of bearing faces, a hinge pin extending beyond the ends of said lug, a lid for closing said box formed to engage said pin on opposite sides of said lug, spring means at one end bearing against the outer face of said lid near its center and at the other end being supported by one or the other of said bearing faces and a stirrup mounted on the hinge pin independent of the lid and constructed so as to be capable of being forced into position on the top of said spring means intermediate its ends.
15. In combination with a journal box provided with a box lug having a plurality of bearing faces, a lid for closing said box provided with extensions located on opposite sides of said lug, a pin for pivotally connecting said extensions to said lug, a spring at one end bearing against the outer face of said lid and at the other end terminating adjacent said lug, a bearing roller threaded onto said spring and bearing on the box lug and a stirrup carried by said pin independently of said lid, rotatable with the lid with relation to said lug and arranged to bear on said spring intermediate its ends and on the opposite side thereof from said lid.
20. In combination with a journal box, a hinge pin extending through the box lug, a pressed steel lid having scrolls surrounding the hinge pin on opposite sides of said lug, a spring at one end bearing against the outer face of said lid near its center and at the other end terminating adjacent the box lug, a bearing member between said lug and the adjacent end of said spring and a tensioning member bearing against said spring on the opposite side thereof from said lid and connected to the hinge pin on opposite sides of said lug and between the same and said scrolls.
25. In combination with a journal box and its box lug provided with a plurality of angularly disposed bearing faces, of a lid hinged to the box lug, and a lid closing device hinged to the box lug on opposite sides and provided with a spring portion operatively positioned in the outer face of the lid at one end and operating with said bearing faces at the other end.
30. The combination with a journal box having a hinge pin lug, of a pin within said lug and projecting therefrom, a lid mounted on said pin, a tensioning member mounted on said pin and a lid closing spring held in place by said tensioning member and bearing against the lid and lug and constructed and arranged to yieldingly hold the lid to its seat on the box.
35. The combination with a journal box, of a hinge pin extending through the lug thereof, a lid having hinge pin engaging portions engaging the hinge pin with relatively great clearances, a lid closing agent at one end operatively engaging the lid intermediate its top and bottom edges and at the other end terminating adjacent the box lug, an anti-friction roller carried by said agent and bearing on said lug and tensioning means for
40. In combination with a journal box provided with a box lug having a plurality of bearing faces, a lid for closing said box provided with extensions located on opposite sides of said lug, a pin for pivotally connecting said extensions to said lug, a spring at one end bearing against the outer face of said lid and at the other end terminating adjacent said lug, a bearing roller threaded onto said spring and bearing on the box lug and a stirrup carried by said pin independently of said lid, rotatable with the lid with relation to said lug and arranged to bear on said spring intermediate its ends and on the opposite side thereof from said lid.
45. In combination with a journal box, a hinge pin extending through the box lug, a pressed steel lid having scrolls surrounding the hinge pin on opposite sides of said lug, a spring at one end bearing against the outer face of said lid near its center and at the other end terminating adjacent the box lug, a roller bearing member between said lug and the adjacent end of said spring and which is threaded onto said spring and a stirrup bearing against said spring on the opposite side thereof from said lid and connected to the hinge pin on opposite sides of said lug and between the same and said scrolls.
50. In testimony whereof, I have hereunto subscribed my name this fifth day of March, 1923.
- LEIGH W. HOSTETTLER.
